United States Patent

Des. 235,633
Patented July 1, 1975

235,633

VEHICLE MUD GUARD

Cecil L. Cooper, 300 E. John, Carson City, Nev. 89701

Filed July 26, 1973, Ser. No. 382,680

Term of patent 14 years

Int. Cl. D12—16

U.S. Cl. D12—185

FIG. 1 is a front perspective view of a vehicle mud guard showing my new design;

FIG. 2 is a front perspective view thereof to an enlarged scale; and

FIG. 3 is a rear perspective view thereof.

The broken lines in the drawing are for illustrative purposes only.

I claim:

The ornamental design for a vehicle mud guard, as shown and described.
